UNITED STATES PATENT OFFICE.

GEORGE D. SHOOP, OF ROCK ISLAND, ILLINOIS.

RAILWAY-CROSSING.

No. 878,677.

Specification of Letters Patent.

Patented Feb. 11, 1908.

Application filed April 9, 1907. Serial No. 367,166.

To all whom it may concern:

Be it known that I, GEORGE D. SHOOP, a citizen of the United States, residing at Rock Island, in the county of Rock Island and 5 State of Illinois, have invented certain new and useful Improvements in Railway-Crossings, of which the following is a specification.

My invention relates to improvements in railway crossings in which a construction is 10 provided entirely obviating the jolting and jarring due to the passage of the wheel treads over the open spaces provided at these joints for the passage of the wheel flanges.

My invention consists broadly in combining guarding means (generally comprising separate guard rails) with the above mentioned means for preventing jarring at the crossing and in constructing both of said means removable and renewable with relation to the rails.

My invention also consists in providing novel means for supporting said removable parts in their places.

My invention further consists in the details 25 of construction arrangement and combination hereinafter described with reference to the accompanying drawings, in which,

Figure 1 is a plan view of a railway crossing provided with my improvements, Fig. 2 30 is a section on the line 2—2 of Fig. 1 looking in the direction of the arrows, Fig. 3 is a similar view to Fig. 2 with the detachable portions removed, Fig. 4 is a perspective view of one of the removable sections, Fig. 5 35 is a perspective view of a section of a rail showing novel means for supporting the removable parts, and Fig. 6 is a similar view of the same used as a supplemental support on a different style rail.

Referring to the figures 1 indicates the rails comprising the track A and 2 indicates the rails comprising the track B. The corner or crossing pieces of said rails are connected thereto by a suitable fish plate 3 and 45 have their head flanges 4 constructed on a lower plane than the head flanges 5 of the main rails as shown clearly in Fig. 3. On the depressed head flanges 4 of the crossing pieces are adapted to be inserted the removable 50 jar preventing plates 7 comprising a base, portion 8 gradually increasing in thickness toward the intersection of the rails and having an interlocking extension 8^a adapted to lie between the heads of the rails forming 55 the crossing piece which may be of one piece if it is so desired. The base portion 8 is pro-

vided with an upstanding shoulder 9 gradually increasing in height from the head flanges 5 to the height of the heads of the crossing piece 6 and being beveled to fit the 60 correspondingly beveled portion of the abutting head of the adjacent rail when in place.

The removable central plates 10 may be formed in one single piece, comprising a base portion 11 of a uniform thickness and equal 65 to the greatest thickness of the base portion 8, and an upstanding guarding flange 12 of a uniform height and equal to the highest point of the flange 9, said plate 10 being substantially square in shape and adapted to be 70 inserted in the head flange 4 of the crossing piece extending inside of the four intersecting points. Thus it will be seen that when a car approaches the crossing on the rails 1, the flanges of the wheels will, upon reaching the 75 crossing piece 6, ride up on the base portions 8, the guards 9 and the heads of the rails preventing side slipping, and will continue on the thickened base portions 11 of the central piece, the faces of the wheels being held from 80 contact with the heads of the rails until the flanges thereof have again reached the main rails on the far side of the crossing thus preventing any jarring whatsoever. It will also be seen that by means of the integral 85 guards 9 and 12 on the removable plates I effectively prevent derailment while crossing. It will further be seen that by constructing the jar preventing plates removable, the same being simply bolted to the 90 head flanges and the heads of the bolts placed uppermost and countersunk, I am able to easily and quickly renew the same as there is immense wear upon them.

In Fig. 5 I have shown my removable 95 plates carried by a railroad rail by means of a supporting T-shaped beam 13 bolted to the web of the same and having its base resting upon the flanged base thereof. On the upper face of the beam 13 the said removable 100 plates are adapted to be secured, the said upper face lying on a plane with the lower portion of the head of the main rail as shown.

In Fig. 6 I have shown the same supporting T-shaped beam applied to a rail such as 105 shown in the other figures, the upper and lower faces of said beam being shaped to fit between the head flange and the base flange respectively of the rail. Thus a strong support is provided for the head flange of the 110 rail which must sustain the entire weight of the car as it passes over the crossing.

Having fully described my invention, what I claim is:

1. In a railway crossing, the combination with removable plates arranged on the head flanges of the rails and gradually increasing in thickness toward the points of intersection, of a removable plate arranged on the head flanges of the rails inside the crossing and extending continuously between the points of intersection of said rails, substantially as described.
2. In a railway crossing, the combination with removable plates arranged on the head flanges of the rails and gradually increasing in thickness toward the points of intersection, of a removable plate arranged on the head flanges of the rails inside the crossing and extending continuously between the points of intersection of said rails, and guard rails formed on said plates, substantially as described.
3. In a railway crossing, the combination with the crossing piece of removable plates arranged on the head flanges of the rails adjacent and leading to the crossing and gradually increasing in thickness toward the points of intersection of the rails, guide rails formed integral with said plates and increasing in height as said plates increase in thickness, and removable plates arranged on the head flanges of the rails between the points of intersection, said last named plates being of a uniform thickness and having guard rails integral therewith and of a uniform height substantially as described.

4. In a railway crossing, the combination with removable plates held adjacent the heads of the rails leading to the points of intersection, guard rails formed integral with said plates, and supporting means therefor, arranged upon the lower flange of the rails and connected to said rail, substantially as described.

5. In a railway crossing, the combination with a set of removable plates held adjacent the heads of the rails and gradually increasing in thickness toward the points of intersection, guard rails formed integral with said plates, a second set of removable plates held adjacent the heads of the rails between the points of intersection, guard rails formed integral with said plate, and support for said plates arranged on the lower flange of the rail and connected to said rails, substantially as described.

6. In a railway crossing, the combination with a set of removable plates carried by the head flange of the rail adjacent the crossing and gradually increasing in thickness toward the points of intersection, of supporting means for said flanges and said plates arranged on the lower flange of the rail and connected to said rail, substantially as described.

In testimony whereof I affix my signature in presence of two witnesses.

GEORGE D. SHOOP.
